3 Claims. (Cl. 137—625.29)

The present invention relates to reversible refrigerating systems and more particularly to a reversing or transfer valve for effecting reversal of refrigerant flow through the heat exchanger components of the system.

One object of the present invention is to provide a new and improved reversing valve for directing the flow of refrigerant through a reverse cycle refrigerating system.

A further object of the invention is to provide a reversing valve of simple and low cost construction and which does not require unloading or pressure equalization of the system to facilitate operation of the valve.

A further object of the invention is to provide an automatic reversing valve including a two-way pressure-actuated piston arrangement for reversing the valve and means operated upon the movement of the valve to one or the other of its two operating positions for equalizing the pressures on opposite sides of the piston and conditioning the valve mechanism for a subsequent operation.

Further objects and advantages of the present invention will become apparent as the following description proceeds, and the features of novelty which characterize the invention will be pointed out with particularity in the claims annexed to and forming a part of this specification.

In carrying out the objects of the present invention there is provided a reversing valve which is adapted to direct the flow of high pressure refrigerant from a compressor to either of two series-connected heat exchangers and to return low pressure refrigerant from the other of the heat exchangers to the compressor. The valve comprises a valve plate and a casing which cooperate to define a gas tight valve housing. The casing has a high pressure refrigerant inlet port communicating with the housing while the valve plate includes a surface within the housing which forms a valve seat having therein a suction or outlet port for connecting the valve to the compressor suction line and two additional ports respectively connecting the housing to each of the two heat exchangers. The heat exchanger ports are spaced equidistant from the suction port so that a valve member having one end connected to the suction port and the other end slidably supported on the valve seat and which is mounted for pivotal movement about the suction port can connect the suction port to either one or the other of the two heat exchanger ports. By this arrangement, high pressure refrigerant entering the housing through the inlet port passes out of the valve housing through whichever heat exchanger port is not covered by the valve member and to the heat exchanger connected to that port while low pressure refrigerant from the other heat exchanger is directed through the valve member and back to the compressor through the suction port. For the purpose of moving the valve member from one or the other of its two operating positions, there is provided a cylinder outside the housing and between the suction and heat exchanger ports and a piston slidably arranged within the cylinder and dividing the cylinder into a control cham-

2

ber and a second chamber. The piston is operatively connected to the valve member by means of a lever extending through the valve plate and pivotally mounted therein. By creating a pressure differential across the piston, the valve member operatively connected thereto is actuated to one or the other of its operative positions and for this purpose, means are provided for connecting one of the chambers within the cylinder either to the high pressure line connected to the inlet port or to the low pressure line connecting the outlet or suction port of the valve to the compressor. In order to equalize the pressures across the piston after such actuation of the valve member and to condition the reversal of the valve member, there is provided a slide valve operated by the valve member and designed to control the flow of refrigerant through a passageway leading from the second chamber to the valve housing. In one position of the slide valve, the housing end of the passage is in communication with a second passage having one end opening into the valve seat and the other connected to the suction port while in a second position of the slide valve, the first mentioned passage is in direct communication with the high pressure refrigerant in the housing. The operation of the slide valve is such that after completion of the piston stroke, refrigerant at the same pressure as that employed in the control chamber for the purpose of effecting the stroke is introduced into the second chamber thereby equalizing the pressures across the piston and conditioning the control cylinder for a subsequent operation of the piston, to reverse the position of the valve member.

For a better understanding of the invention, reference may be had to the accompanying drawing in which:

Fig. 1 is a diagrammatic illustration of the heat pump or reversible refrigerating system provided with a reversing valve embodying the present invention;

Fig. 2 is an enlarged view, partially in section, of the valve of the present invention;

Fig. 3 is an elevational sectional view along line 3—3 of Fig. 2;

Fig. 4 is a sectional view along line 4—4 of Fig. 2;

Fig. 5 is a detailed sectional view along line 5—5 of Fig. 2 illustrating the slide valve in one operating position;

Fig. 6 is a view similar to Fig. 5 showing a second operative position of the slide valve illustrated in Fig. 5; and

Fig. 7 is a sectional view along line 7—7 of Fig. 5.

Referring now to Fig. 1 of the drawing, the reversible refrigerating system disclosed comprises an indoor heat exchanger 1 and an outdoor heat exchanger 2 which are connected in series through an expansion valve 3 whereby the heat exchanger 1 can be employed for either heating or cooling the air from within an enclosure depending upon the direction of flow of refrigerant through the two heat exchangers.

Refrigerant is circulated through the heat exchangers by means of a compressor 4 while the valve 5, forming the subject matter of the present invention, controls the direction of flow of refrigerant through the heat exchanger so that the heat exchanger 1 can function either as the condenser or as the evaporator component of the refrigerating system. In this system high pressure refrigerant from the compressor flows through the compressor discharge line 7 and through the valve 5 to either the indoor heat exchanger 1 through the indoor conduit 8 or to the outdoor heat exchanger 2 through the conduit 9. Low pressure refrigerant from the heat exchanger functioning as the evaporator returns to the compressor through the valve 5 and the suction line 11.

Referring now more particularly to Figs. 2, 3, and 4 of the drawings, the reversing valve 5 of the present inven-

tion comprises a valve plate 12 and a casing 14 which cooperate to form a gas tight housing 15 into which high pressure refrigerant is introduced through the inlet port 16 connected to the compressor discharge line 7.

The valve plate 12 forming one wall of the housing 15 is preferably composed of a plurality of layers for reasons which will be given hereinafter and includes a smooth flat inner surface forming a valve seat 17 within the housing 15. Provided in the flat surface portion of the valve seat 17 are spaced heat exchanger ports, the port 18 communicating with the heat exchanger conduit 8 and the port 19 communicating with the heat exchanger conduit 9. Spaced equidistant from these two ports is a suction port 20 which is in communication with the suction line 11 and which preferably comprises a tubular portion extending slightly above the surface of the valve seat 17.

For the purpose of connecting one or the other of the two heat exchanger ports with the suction port 20, there is provided a valve member 21 having one end 22 pivotally mounted on the upwardly extending portion of the suction port 20 and the other end 23 slidably supported on the valve seat 17 whereby the suction port 20 can be connected through the substantially U-shaped passage-way 24 within the valve member 21 with either of the heat exchanger ports 18 and 19 by pivotal movement of the valve member 21 about the suction port 20. A tension spring 26 having one end extending into the passage 24 and connected to the valve member 21 and the other end extending through the suction port 20 and connected by means of a pin 27 to the walls of the port serves to hold the valve member 21 in engagement with the port 20 and the valve seat 17 regardless of the positioning of the valve 5. Preferably, this spring 26 is positioned centrally of the port 20 and hence in line with the axis of rotation of the valve member 21. Means for limiting movement of the valve member 21 in either direction so that the passage 24 is in line with one or the other of two heat exchanger ports 18 and 19 is provided in the form of flanges 29 and 30 extending outwardly from the sides of the valve member 21 for engagement with the wall of the casing.

Means for shifting the valve from one to the other of its two operating positions includes a piston 32 slidably arranged within a cylinder 33, the piston 32 dividing the cylinder into a control chamber 34 and a second or pressure equalizing chamber 35. As indicated in Fig. 3, the cylinder 33 is disposed outside of the housing 15 and below the valve plate 12 about mid-way between the suction port 20 and the two heat exchanger ports 18 and 19. The piston 32 is loosely connected to the valve member 21 by means of a lever 41 which is pivotally mounted in the valve plate 12 employing a gas tight packing 36 and which has one end 37 loosely disposed in a slot 38 in the piston 32 and the other end 39 loosely disposed in a slot 40 on the bottom portion of the valve member 21.

By this arrangement it will be seen that movement of the piston from one end to the other of the cylinder 33, which extends in a direction generally parallel to the direction of travel of the end 23 of the valve member, causes the valve member 21 to pivot about the suction line 20 in the opposite direction, travel of the valve member in either direction being limited by the flanges 29 and 30. In order to obtain this valve actuating movement of the piston 32 within the cylinder 33, the control chamber 34 is connected through a control tube 43 to either the high pressure or discharge line 7 from the compressor of the suction line 11 depending upon the then existing value of the pressure in the equalizing chamber 35. As is shown in Fig. 1 the control tube 43 can be connected by a three-way solenoid valve 45 to either the compressor discharge line 7 through a conduit 46 or to the suction line 11 through the conduit 47.

In order to equalize the pressures on opposite sides

of the piston 32 following the operation of the valve and condition the valve for a subsequent reverse movement there is provided a slide valve 51 slidably arranged on the surface of the valve seat 17 beneath the flange 29 for connecting the chamber 35 through a passage 52 with either the low or high pressure sides of the refrigerating system only after the valve member 21 has completed most of its travel from one operating position to the other. The slide valve 51 is held in sliding engagement with the valve seat 17 by a bracket 54 secured to the valve seat by bolts 55 and a spring collar 57 which bears against the lower side of the bracket 54. A slot 58 through which the projection 59 forming a part of the valve 51 extends is provided in the bracket 54 for the purpose of defining the path and limiting the movement of the valve 51 relative to the valve seat 17.

For the purpose of connecting the passage 52 with low pressure or suction refrigerant there is provided in the valve plate 12 a suction gas passage 61 which is indicated in Figs. 2, 5 and 6 and which connects at one end to the suction port 20 and at the other end opens through port 62 onto the valve seat 17. In order to form the suction passage 61, the valve plate 12 comprises a plurality of layers, the upper layer forming the valve seat 17 having the passage or opening 62 provided therein while the next layer indicated by the numeral 64 has a connecting slot extending from the lower end of the opening 62 to the suction port 20.

Actuating of the slide valve 51 by the valve member 21, is obtained by means of a slot or recess 67 of arcuate shape in the flange 29 which encompasses the projection 59 and is of a length such that near the end of the travel of the valve member 21 in either direction, the position of the slide valve 51 will be reversed. In one position of the slide valve 51, the recess 71 formed in the lower part of the valve overlies the suction port connection 62 and the passage 52 to the cylinder chamber 35 as shown in Fig. 5 so that the chamber 35 is in communication with the low or suction pressure side of the system and hence at a low or suction pressure. In the reverse position of the valve 51 as shown in Fig. 6, the passage 52 is in communication with the interior of the housing 15 so that the chamber 35 will be at the higher discharge pressure of the system since the housing 15 is always at this pressure. To provide for this latter communication, it may be desirable to form the spring collar 57 with a plurality of slots 73 so that open communication is obtained between the passage 52 and the housing 15 through the slot 58 provided in the bracket 54.

By this arrangement, movement of the valve member 24 to either of its two operating positions is assured even in those cases where the valve may be in an intermediate position as for example as a result of jiggling of the structure during shipment. With the valve in the position shown in Figs. 2, 3, 4, and 5, the control chamber 34 is at suction pressure as is also the chamber 35 since this chamber is connected to the suction line through the auxiliary valve 51 and passages 52 and 61. The pilot valve 45 connects the line 43 to the suction conduit 11 through the line 47. The indoor coil 1 is functioning as a condenser and the outdoor coil 2 as an evaporator so that the system is conditioned for heating the enclosure which it serves.

When cooling is called for, the solenoid valve 45 is actuated to connect the control chamber 34 to high or discharge pressure. This high pressure drives the piston 32 to the right as viewed in Fig. 4 thus causing the lever 41 to drive the valve member 19 to the left and into its operating position with regards to the heat exchanger port 18. During this transfer of the valve member 19 both of the heat exchanger ports 18 and 19 are exposed for a short time to the high pressure existing within the housing 15 so that there is at least some equalization of pressures in these two heat exchangers during the valve transfer.

As to the operation of the auxiliary valve 51, it is not until the main valve member 19 has been shifted to practically the end of its travel, for example, into communication with the port 18, that the walls of the slot 67 engage the projection 59 and cause the auxiliary valve 51 to move to the position shown in Fig. 6, that is, the position in which the passage 52 is in communication with the higher or discharge pressure gas within the housing 15. Thus during this transfer, the second chamber 35 is at suction pressure to maintain a positive pressure differential across the piston until the valve transfer is substantially complete at which time the shift of the auxiliary valve 51 then connects the chamber 35 to discharge pressure in order to equalize the pressures on the opposite sides of the piston 32 within the cylinder 33 and set up the pressure conditions in the cylinder 34 required for the subsequent reversal of the valve.

In order to shift the valve to its position connecting the compressor discharge with heat exchanger, the control chamber 34 is connected to the suction line 11 through the valve 45 and with the delayed action of the auxiliary valve 51 the resultant pressure differential across the piston 32 shifts the valve member 21 into operative position with port 18. Thus it will be seen that while both shifting operations are dependent upon the pressure differentials across the piston 32, they are independent of the pressure conditions existing within the housing 15 although the high or discharge pressure within the housing 15 does help to maintain the valve member in seated relationship on the valve seat 17.

While there has been shown and described a particular embodiment of the present invention, it is to be understood that the invention is not limited thereto, and it is intended by the appended claims to cover all modifications within the true spirit and scope of the invention.

What we claim as new and desire to secure by Letters Patent of the United States is:

1. A reversing valve comprising a valve plate and a casing defining a gas tight housing, said valve plate including a surface within said housing forming a valve seat, said casing having a high pressure inlet port, said valve seat having a plurality of ports opening into said housing and including a low pressure outlet port and two additional ports spaced equidistant from said low pressure port, a valve member having a valve passage communicating at one end with said low pressure outlet port, the other end of said valve member being slidably supported on said valve seat, said valve member being pivotally mounted adjacent said one end of said passage for pivotal movement about said low pressure outlet port for movement of the other end of said valve passage between two limiting positions communicating with said respective additional ports, and means for actuating said valve member from either of said limiting positions to the other comprising a cylinder generally disposed outside said housing between said low pressure outlet port and said additional ports and extending in a direction substantially parallel to the direction of movement of said other end of said valve passage between said additional ports, a piston slidably disposed in said cylinder and dividing said cylinder into a control chamber and a second chamber, a lever pivotally supported by said valve plate and having one end in engagement with said valve member and the other end engaged by said piston whereby movement of said piston effects pivotal movement of said valve member to either of said positions, means for creating a pressure differential across said piston to effect movement thereof within said cylinder comprising means for connecting said control chamber with either said inlet port or said low pressure outlet port and means for equalizing the pressures across said piston upon completion of a piston stroke comprising a first passage extending through said valve plate and having one end communicating with said second chamber and the other end opening into said housing, a low pressure passage extending

from said low pressure outlet port through said valve plate and terminating in said housing on the face of said valve plate adjacent said first passage, a slide valve slidably arranged on said valve seat in operative relationship with the housing ends of said passages, and means carried by said valve member for engaging said slide valve when said valve member approaches either of its limiting positions to move said slide valve to a position in which the pressure in said second chamber becomes the same as that existing in said control chamber.

2. A reversing valve comprising a gas-tight housing including a flat surface within said housing forming a valve seat, said housing including an inlet port, said valve seat having a plurality of ports opening into said housing and including an outlet port and two spaced-apart additional ports spaced equidistant from said outlet port, a valve member slidably supported on said valve seat and having a valve passage communicating at one end with said outlet port, said valve member being pivotally mounted adjacent said one end of said passage for pivotal movement about said outlet port for movement of the other end of said valve passage into operative position with one or the other of said additional ports, spring means for maintaining said valve member in engagement with said valve seat, and means for actuating said valve member from either of said operative positions to the other comprising a cylinder disposed between said outlet port and said additional ports and extending in a direction generally parallel to the direction of travel of said other end of said valve passage, a piston slidably disposed in said cylinder and dividing said cylinder into a control chamber and a second chamber, a lever having one end in engagement with said valve member and the other end engaged by said piston, means for selectively connecting said control chamber to said inlet port or to said outlet port for effecting movement of said valve member from one operative position to the other, and means for equalizing the pressures across said piston when said valve member approaches said other position comprising a first passage extending through said valve plate and having one end communicating with said second chamber and the other end opening into said housing, a second passage extending from said outlet port through said valve plate and terminating on the face of said valve plate adjacent said first passage, a slide valve slidably arranged on said valve seat in operative relationship with the valve seat ends of said first and second passages, a slot in said valve member, a projection on said slide valve extending into said slot, said slot being of a length such that as said valve member approaches either of its operating positions an end of said slot engages with the projection to actuate said slide valve to a position in which the pressures in the two chambers are equalized.

3. A reversing valve comprising a valve plate and a casing defining a gas-tight housing, said valve plate including a surface within said housing forming a valve seat, said casing including an inlet port, said valve plate including an outlet port and two additional ports spaced equidistant from said inlet port, said outlet port having an annular end portion extending into said housing, a valve member having a passage communicating at one end with said outlet port, said valve member being slidably supported on said valve seat and pivotally mounted on said annular end portion of said outlet port for pivotal movement thereabout to bring the other end of said passage into communication with either of said additional ports, means on said valve member for engaging said casing to limit pivotal movement of said valve member to a first operating position communicating with one of said additional ports and a second operating position communicating with the other of said additional ports, a tension spring for maintaining said valve member in engagement with said valve seat, said spring having one end extending into said passage and connected to said

valve member and the other end anchored in said outlet port, and means for actuating said valve member from either of said operating positions to the other comprising a cylinder generally disposed outside said housing between said outlet port and said additional ports and extending in a direction substantially parallel to the direction of movement of said other end of said passage between said additional ports, a piston slidably disposed in said cylinder and dividing said cylinder into a control chamber and a second chamber, a lever pivotally supported by said valve plate and having one end in engagement with said valve member and the other end engaged by said piston whereby movement of said piston will effect pivotal movement of said valve member to either of said operating positions, and means for creating a pressure differential across said piston to move said valve member from one operative position to the other comprising means for selectively connecting said control chamber to either said inlet port or said outlet port and means for equalizing the pressures across the piston upon completion of a valve member movement comprising an equalizer passage extending through said valve plate and

5
10
15

having one end communicating with said second chamber and the other end opening into said housing on said valve seat, a second passage extending from said outlet port through said valve plate and terminating on the face of said valve plate adjacent said first passage, a slide valve slidably arranged on said valve seat in operative relationship with the housing end of said equalizer passage, a slot in said valve member, a projection on said slide valve extending into said slot, said slot being of a length such that as said valve member approaches either of its operating positions, an end of said slot engages said projection to actuate said slide valve to a position in which said second chamber is brought to the same pressure as said control chamber.
